CLAIM

The ornamental design for an anti-rattle device and bolt as shown and described.

DESCRIPTION

FIG. 1 is a perspective view of an anti-rattle device and bolt showing my new design how it appears completely assembled;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is an exploded view of all the parts thereof;

FIG. 9 is a cross-sectional view of the invention in an initial phase thereof;

FIG. 10 is a cross-sectional view of the invention in finished phase thereof; and,

FIG. 11 is a cut-away view of the internal parts thereof.

In the drawings, the broken lines depict portions of the anti-rattle device and bolt that form no part of the claimed design.
